UNITED STATES PATENT OFFICE.

LUDWIG ALFRED BODLER, FRITZ KUMMER, AND FRITZ PAULI, OF LUCERNE,
SWITZERLAND.

APPARATUS FOR PRINTING THE POSTAGE ON GOODS TO BE MAILED.

Application filed May 26, 1921. Serial No. 472,857.

To all whom it may concern:

Be it known that we, LUDWIG ALFRED BODLER, a citizen of the Republic of Germany, residing at Lucerne, FRITZ KUMMER, a citizen of the Republic of Switzerland, residing at Lucerne, and FRITZ PAULI, a citizen of the Republic of Switzerland, residing at Lucerne, Switzerland, have invented certain new and useful Improvements in Apparatus for Printing the Postage on Goods to be Mailed; and we do hereby declare the following to be a clear, full, and exact description of the invention, such as will enable others skilled in the art to which it appertains to make and use the same, reference being had to the accompanying drawings and to letters or figures of reference marked thereon, which form a part of this specification.

This invention relates to improvements in apparatus for printing the postage on goods to be mailed, such as printed matter, samples, post-cards, letters, addresses of parcels and the like thus replacing postage stamps so that private firms will utilize the above apparatus under the control of the post-office authorities. The apparatus may to this end indicate the total amount due corresponding to the number of impressions made, and the firm may pay the postage fees in a manner similar to that in which it pays for electricity, gas or water consumption according to the indications of a meter.

The apparatus according to the invention consists of a plurality of dies for different values of the postage which can be singly brought into an operative position, and of a device for each die for adding the number of impressions effected by each die.

A constructional example of the apparatus according to the invention is shown on the accompanying drawing in which:

Fig. 1 is a plan view of the apparatus on a small scale,

Fig. 2 is a vertical cross-section on an enlarged scale and along line II—II of Fig. 1,

Fig. 3 is a vertical cross-section along line III—III of Fig. 1,

Fig. 4 is a vertical longitudinal section along line IV—IV of Fig. 2,

Fig. 5 is a horizontal section on line V—V of Fig. 2, parts of the apparatus being shown in plan view,

Figs. 6 and 7 show details of the appara-

tus and of parts thereof in different working positions.

1 denotes a cast-iron base plate to which a cover 2 is detachably connected. A member 3 is fitted to said base plate 1 and provided with two U-shaped slots 4 and 5 adapted to act as vertical guides to the inker pad 6 and to the impact member or platen 7. To the member 3 the part 8 is rigidly fixed in which the horizontal guide means 9 for the stamp die carriers 10 are provided to which the stamp dies 11 are fitted. On a longitudinally arranged horizontal shaft 12 two levers 13, one of which is provided with a handle, are fixed, by means of which handle an angular movement may be imparted to said shaft. Levers 14 are fixed to said shaft which cooperate with the under side of a bar 15 of a channel cross-section carrying the inker pad 6 and being adapted to glide vertically up and down in the guide slot 4. The die carrier 10 of each die 11, six such dies are shown in the apparatus illustrated and are arranged parallel to each other, is adapted to glide in a horizontal direction in the guides 9. Each die carrier 10 is provided with a pin having a square head 16 with which two lugs 17 (Fig. 3) extending in the longitudinal direction of the apparatus are in engagement. Said lugs 17 form part of a slide 18 adapted to be displaced in the longitudinal direction of the apparatus on the main slide 19, the latter being displaceably arranged in the transversal direction in guide means 20 (Fig. 3) provided on the part 8. For the purpose of imparting a to and fro movement to the main slide 19 two levers 21 are rotatably mounted on the shaft 12 and are provided at their right hand side (when seen in Fig. 2) with a projecting facing 22. Two bolts 23, 24 respectively, fixed to the levers 13 cooperate with said facings and with the other side of said lever 21 respectively upon a turning of said levers 13 in one or the other direction. The levers 21 are connected by means of links 25 to the main slide 19. Thus, upon an oscillating motion of the hand lever 13 the main slide 19 is moved to and fro in its horizontal guides and that stamp 11 the square part 16 of the carrier of which is in engagement with the lugs 17 of the slide 18 takes part in the movement of the main slide 19. The relative position between the bolts 23 and

24 on the levers 13 and the parts of the levers 21 with which said bolts cooperate is such, that the levers 13 perform an idle movement before the bolts 23, 24 contact 5 with the levers 21. In consequence thereof upon a turning motion of the hand lever 13 from the position shown in Fig. 2 in the direction of the arrow towards the left, the lever 14 is first turned towards the base 10 plate 1 and the carrier part 15 supporting the pad 6 performs a lowering movement owing to its weight and moves away from the stamp 11. Thereafter the bolts 23 abut against the facings 22 and cause a movement 15 of the die 11 in the direction of the arrow shown. In this way a rubbing of the die 11 on the pad is prevented. When the hand lever is moved from its extreme left position towards the right, which movement 20 can be effected by a spring 55, the die 11 is moved towards the right and the pad 6 is raised again by the action of the lever 14.

Towards the two ends of the shaft 12 there are further arranged two levers 25 25 rotatably mounted on said shaft the free ends of said levers being provided with cylindrical rods 26 extending in the direction of said levers. On the rods 26 double armed levers 27 are swingably mounted the 30 free ends of said levers being provided with rollers 28 and 29 respectively. The two lateral ends of the impact member 7 are provided with projections 30 (Figs. 4 and 7) which, seen in elevation, are of a triangular 35 shape, the upper side of the triangle being horizontally arranged. The upper rollers 28 coat with said upper side of the triangles and cause the impact member 7 to be lowered in the guide 5 upon a turning of the 40 hand lever 13 in the direction of the arrow. To transmit the turning motion of the levers 13 to the levers 25 the former are provided with projecting facings 31 which abut with facings 32 provided on the levers 25. 45 Upon the lowering of the impact member 7 the lower rolls 29 of the levers 27 come into engagement with the rounded head 33 of bolts screwed into the base plate 1 and projecting into the path of said rolls 29. There- 50 upon the levers 27 are caused to turn around their fulcrum rods 26, whereby the rollers 28 are brought out of engagement with the upper side of the triangular projections and release the impact member 7. Fig. 7 illus- 55 trates the position of the lever 27 at this moment. The lowering movement of the impact member 7 causes a compression of the springs 34, of which two are provided and which now impart a rapid upwards 60 movement to the impact member 7 towards the die 11, which meanwhile has been brought into its operative position (illustrated in Fig. 6) by the turning movement of the hand lever 13 as has been described 65 above. In this way the value correspond-

ing to the postage and engraved in the operative die 11 is printed onto an envelope or the like inserted between the impact member 7 and the stamp 11. When the hand lever 13 is turned in the direction opposite to the arrow shown in Fig. 2, the free ends of the levers 35 fixed on the shaft 12 contact with facings 36 and cause a turning motion of the levers 25 in an anti-clockwise direction. During this movement the upper rolls 28 of the levers 29 glide along the inclined sides of the triangular projections 30 and, as soon as they pass the corner of said projections, swing by the action of the weight of the levers 29 around the fulcrums 26, so that the rolls 28 are again in engagement with the horizontal sides of the projections 30. 75

For the purpose of printing different values corresponding to different postage fees for mail matter a special die 11 for each value is provided in the apparatus. To select the desired value and cause the stamp corresponding to that value to become operative the slide 18 can be moved in the longitudinal direction of the apparatus on the main slide 19 so that its lugs 17 can be brought into engagement with the square head 16 of the desired die carrier 10. The slide 18 is provided with a knob 37 projecting above the top part of the cover 2. In connection with the knob 37 a plate 38 is provided to which a hand 39 is fixed (Fig. 3), which indicates on number plates 40 the value to be printed by the operative die 11. 85 In order to secure the slide 18 in the desired position a pin 41 is operatively connected to the plate 38 and is pressed by the action of a spring 42 into holes 43 corresponding to the proper position in which the operative 90 connection between the slide 18 and the desired die is effected. A stop 44 is further fixed to said plate 38 and extending into the opening 45 of the cover into which the envelopes and the like to be stamped are inserted. The lower end of the stop is in contact with the horizontal ledge 46 on which the envelopes are placed, the latter being moved in the longitudinal direction of the apparatus until they rest with one of their lateral edges against the stop 44 which position then ensures the stamp being printed in the right hand corner of the envelope card, address slip or the like. 100

The device for adding the impressions effected by every die consists of the following parts: Each die carrier 10 is provided at its rear end with a rod like extension 47 which is guided on its upper half by an extending portion of the guide member 8. The outer 105 end of each rod 47 is provided with an oblique cam face 48, which, on the forward movement of the stamp carrier 10, coacts with an oblique facing 49 provided on a turnably mounted organ 50 and causes a dis- 110

placement of said facing 49 and thereby a turning motion of the organ 50 in an anti-clockwise direction around its fulcrum. A spring loaded pawl 51 which is in engagement with the toothed part of counter wheels 52 of the jumping figure type is mounted on the organ 50 and causes a turning motion of the wheels 52 through the extent of one tooth upon the turning of organ 10 50. A plate spring 53' brings the organ 50 back into its initial position. To every counter wheel 52 provided with the figures a ratchet wheel 53 is rigidly fixed, which is provided with a slot 54 extending across the 15 whole width of the teeth between the teeth corresponding to the Figures 9 and 0. The pawl 51 is provided with the same number of prongs as the number of counting wheels with which it cooperates and pushes in a 20 tangential direction against the ratchet wheels. The prong which cooperates with the counter wheel which represents the single figures is the longest and the adjacent prongs cooperating with the following 25 wheels (the wheels representing the tens, hundredths and thousands) are shorter by the height of the teeth of the ratchet wheels. When, now, the wheel counting the single figures has been shifted to the Figure 9, the 30 prong coacting with this wheel enters the notch between the Figures 9 and 0 and the next prong (coacting with the wheel indicating the tens) becomes operative and shifts the next wheel by one tooth and so on. 35 Pawls 54' are further provided for preventing a return movement of the counting wheels.

We claim:

1. In an apparatus for printing the postage on mail matter, the combination of a plurality of independently movable dies corresponding to different postage values, means to bring any one of the dies into a printing position, a hand lever for operating the apparatus, an impact member operatively connected to said hand lever and adapted to cause the matter to be printed upon to be pressed against the selected die, and means to add the number of impressions made by 40 any of the dies.
2. In an apparatus for printing the postage on mail matter, the combination of a plurality of dies corresponding to different postage values inking means for said dies, 45 means adapted to be operatively connected to any one of the dies for moving the selected die from its inking position into its operative position, means to effect the operative connection of any one of said dies with the means causing said movement of the 50 selected die, a hand lever operatively connected to the means causing the movement of the selected stamp, an impact member operatively connected to said hand lever and adapted to cause the mail matter to be printed upon to be pressed against the operative stamp, and means to add the number of impressions made by any of the stamps.
3. In an apparatus for printing the postage on goods to be mailed, the combination of a plurality of dies corresponding to different values, inking means for said dies, means adapted to be operatively connected to any one of the dies for moving the selected die from its position to its operative position, means to effect the operative connection of any one of said dies with the means causing said movement of the die, a hand lever operatively connected to the means causing the movement of the 55 selected die, means adapted to cause a movement of the inking means before the movement of the selected die into its operative position is started, an impact member operatively connected to said hand lever and 60 adapted to cause the mail to be printed upon to be pressed against the operative die, and means to add the number of impressions made by any of the dies.
4. In an apparatus for printing postage on letters and the like, the combination with independently movable printing dies and inking mechanism therefor; of manually operated die-selecting mechanism, an operating handle, means to move the inking mechanism during the initial period of movement of said handle, means actuated by the handle to move the selected die into printing position, a spring-actuated platen released by said handle after the die has 65 moved into printing position, and registering mechanism operated by each die on its return movement.

In testimony that we claim the foregoing as our invention we have signed our names. 105
